AIR CONDITIONING APPARATUS

Robert R. Candor, Dayton, Ohio, assignor to General Motors Corporation, Dayton, Ohio, a corporation of Delaware

Application July 19, 1934, Serial No. 736,017

8 Claims. (Cl. 62—6)

This invention relates to refrigeration and more particularly to the conditioning of air in rooms and other enclosures.

It is an object of this invention to provide a method and apparatus for conditioning air in a room or the like in such a manner that the necessity for providing drain pipes, water pipes, or the like in the walls or floor of the room is obviated, and in such a manner that only the usual energy supply lines are necessary.

Further objects and advantages of the present invention will be apparent from the following description, reference being had to the accompanying drawings, wherein a preferred form of the present invention is clearly shown.

In the drawings:

Fig. 1 is a diagrammatic representation of one embodiment of my invention;

Fig. 2 is a diagrammatic representation of a slightly modified form of invention; and

Fig. 3 is a diagrammatic representation of another modification of my invention.

In practicing my invention, the air in the room 10, for example, is to be conditioned. To accomplish this, an evaporator or cooling element 11 is provided, and means for thermally contacting the air to be conditioned with the evaporator are provided. This means may take the form of a casing 12 having an inlet 13 for air to be conditioned and an outlet 14 for the conditioned air. The inlet 13 may take air from the room, or from the outside, or both. A fan 15 is provided to circulate the air through the casing, and this fan conveniently may be driven by an electric motor 16.

Means for supplying cooling medium to the cooling unit or evaporator 11 are provided. This means may take the form of a refrigerant liquefying unit in refrigerant circulating relationship with the evaporator 11. The refrigerant liquefying unit may include a refrigerant translating device or compressor 17 located in an insulated compartment 18 in the room. A heat dissipator 19 is located outside of the room and preferably adjacent the window 20. Means are provided for circulating a heat dissipating fluid between the insulated compartment 18 and the heat dissipator 19. In the form shown in Fig. 1 this may be accomplished by locating a refrigerant condenser 21, with suitable vertical metal fins 21a, in the heat dissipator 19. The heat dissipating fluid, in this form being the refrigerant of the system, is circulated or forced in compressed form from the compressor 17 through the line 22 to the condenser 21. The refrigerant condensed therein is

gathered in the receiver 23 and flows through the line 24 back to the room and thus travels in a closed cycle. The propelling force for circulating the fluid to the exterior of the room and back again is derived from the driver of the compressor. A branch 25 is connected to the evaporator 11, an automatic expansion valve 26 being interposed. The valve 26 may be of the automatic type which feeds liquid refrigerant when the pressure is reduced in the evaporator below a substantially constant pressure limit the valve also being throttled by the action of a thermostatic bulb 27 located at the refrigerant outlet of the evaporator when liquid refrigerant tends to circulate beyond the evaporator. Another branch of the line 24, indicated at 28, is connected through the medium of another expansion valve 29 with a second evaporator 30. A body of liquid refrigerant is thus maintained in thermal contact with the refrigerant liquefying unit which absorbs any heat generated therein. The valve 29 may be similar to the valve 26 and may be throttled by a thermostatic bulb 31 similar to the bulb 27. The refrigerant evaporated in the evaporators 11 and 30 flows through the pipe 32 to the compressor 17.

The compressor 17 may be driven by a motor 33. A fan 34 is provided for blowing air over the condenser 21, which air flows through the openings 35 and 36, in either direction, depending on the impelling force of the fan 34. The fan 34 may be driven by motor 36. Means may be provided for controlling the operation of the refrigerant liquefying unit and of the motor-driven fan 34. Preferably this control is made responsive to conditions in the room 10 by means of a thermostat, hygrometer or psychrometer 38. This control 38 may be provided with a switch which opens and closes the circuit to the motor 33 and the motor 36 simultaneously, so that the fan 34 and the refrigerant liquefying unit operate in conjunction.

Moisture is generally condensed on the evaporator 11 from the air which is being conditioned. Means are provided for discharging this moisture from the room. To this end, a drip pan 39 is provided to catch the moisture from the evaporator 11. From this a drain pipe 40 leads to a pump 41 driven by the motor 33. The pump 41 discharges through a water pipe 42 to a spray-head or other distributing means 43 which distributes the condensed moisture over the surface of the condenser 21 where the moisture is evaporated and is discharged into the atmosphere outside the room 10. A basin 44 is provided to

catch any excess moisture which may not be evaporated from the surface of the condenser 21, and this basin 44 may be of such extent that any moisture gathered therein eventually will evaporate into the atmosphere without overflow.

All of the lines or pipes leading from the air conditioning apparatus within the room 10 to the heat dissipator 19 conveniently may pass through the window 20 of the room. To this end a block 45 may be provided which may be secured on the window-sill 46 and which thus becomes in effect a new window-sill for the sash 47. The lines, wires, etc., which pass to the heat dissipator 19 may pass through the block 45.

In the modification shown in Fig. 2, a casing 50 is provided for the evaporator 51. An air inlet 52 and an air outlet 53 are provided. The inlet 52 may receive air from the room, from the outside, or both. A fan 54, driven by a motor 55, circulates air to be conditioned in thermal contact with the evaporator 51. A heat insulated compartment 56 is placed in the room, and in this compartment a refrigerant liquefying unit is located which is in refrigerant circulating relationship with the evaporator 51. The refrigerant liquefying unit may take the form of a refrigerant translating device or compressor 57 which discharges compressed refrigerant to the condenser 58. The condensed refrigerant flows through the pipe 59 and through an automatic expansion valve 60 to the evaporator 51, and the evaporated refrigerant returns through the pipe 61 to the compressor 57. The valve 60 may be similar to the valve 26 and may be controlled by the thermostatic bulb 62 in the manner heretofore described with respect to valve 26.

A heat dissipator 63 is located outside of the room. Means are provided for circulating or forcing a heat dissipating fluid in thermal contact with the refrigerant liquefying unit and the dissipator 63. To this end the closed liquid or water circuit includes a water coil 64 from which water is circulated by the pump 65, by force derived from its driving motor, through the heat absorbing coil 66 to the heat dissipating coil 67. The water, after having discharged its heat to the outside atmosphere through the coil 67, returns through the pipe 68 to the coil 64. Thus the heat of liquefaction from the condenser 58, and any other heat generated by the refrigerant liquefying unit is transferred from the insulated compartment 56 through the heat dissipator 63 to the outside atmosphere. The pulleys of the compressor 57 and of the motor 71 may be provided with fan blades which cause a circulation of air within the compartment 56, sufficient to transfer heat from the compressor and motor to the coil 66.

A fan 69 driven by a motor 70 circulates air through the heat dissipator 63 through the openings 71 and 72 in either direction as may be desired. A control 73 similar to the control 38, and placed in the room 74 controls the operation of the refrigerant liquefying unit and of the fan 69 so that the same operate in conjunction in response to conditions in the room 74.

Means are provided for transferring any moisture condensed on the evaporator 51 to the outside of the room. To this end a drip pan 75 discharges into a pump 76 driven by the motor 77, which also drives the compressor 57 and pump 65. The condensed moisture is discharged from the pump 76 through the pipe 77a to the spray-head 78 in the heat dissipator 63. The spray-head 78 discharges the moisture over a wick or

other evaporating means 79 adjacent the condenser 61. Here the moisture is evaporated into the atmosphere outside the room 74, and any excess moisture is gathered into the basin 80 from which it may be evaporated by the wicks 81 without overflowing.

As in the case of the modification in Fig. 1, pipes, wires, etc., connecting the air conditioning apparatus in the room 74 with the heat dissipator 63 may pass through a block 82 secured to the sill 83 of the window 84.

In the modification shown in Fig. 3, air to be conditioned for the room 100 is brought in thermal contact with an evaporator 101. This is accomplished by circulating air from the inlet 102 to the outlet 103 by means of a fan 104 driven by a motor 105. The inlet 102 receives air from the room, outside or both. An automatic valve 106, controlled by a thermostatic bulb 107, may be provided which is similar in construction and function to the valve 26.

A refrigerant liquefying unit is provided in refrigerant circulating relationship with the evaporator 101. This unit conveniently may be located in the insulated compartment 108 located in the room 100. The unit may include a refrigerant translating device or compressor 109 which discharges compressed refrigerant to a condenser 110. The condensed refrigerant is gathered in the receiver 111 from whence it flows to the valve 106 and evaporator 101 through the pipe 112. The evaporated refrigerant returns through the pipe 113 to the compressor 109. The compressor is driven by an electric motor 114.

Means are provided for dissipating the heat generated in the refrigerant liquefying unit outside of the room. This may take the form of instrumentalities for circulating or forcing a liquid in thermal contact with the various parts of the refrigerant liquefying unit and with the heat dissipator 115 located outside of the room. The liquid preferably is water which is circulated from the condenser shell 116 by means of a pump 117 driven by the motor 114. The water then circulates through the heat absorbing coil 118 from whence it flows through the pipe 119 to a liquid evaporative element 120. This element may take the form of wicks over which the liquid is spread and from which it is caused to evaporate partially by air circulated by a fan 121 driven by a motor 122. The portion of the liquid which is not evaporated is gathered in the basin 123 and returns for recirculation in thermal contact with the refrigerant liquefying unit. Means are provided for replenishing the liquid evaporated and this may take the form of a large reservoir 124 placed in the return line 125. This reservoir 124 may be filled by a bucket or the like as it becomes empty. It is to be understood, however, that it may be automatically filled by a float controlled water inlet if a water supply is available. The pulleys of the compressor 109 and motor 114 may be provided with fan blades in a manner similar to the motor 71 and compressor 57 of Fig. 2.

Means are provided for dissipating the moisture condensed on the evaporator 101 outside of the room. Thus a drain pan 126 discharges into a float chamber 127. Here a float controlled valve 128 controls the flow of excess liquid through the pipe 129 to the pump 117. Whenever the liquid in the chamber 127 rises above a predetermined limit, such excess liquid is discharged through the pipe 129 into the pump 117 from whence it is discharged along with the heat dissipating liquid through the coil 118 and pipe

119 to the evaporative element 120 from whence it eventually is discharged into the atmosphere.

A control 130 similar to the control 38 controls the motor-driven fan 121 and the motor 114 so that they operate in conjunction in response to 5 conditions in the room 100.

Any lines between the air conditioning apparatus in the room 100 and the heat dissipator 115 pass through the block 131 secured to the sill 132 of the window 133 in a manner similar to that 10 heretofore described with respect to Figs. 1 and 2.

While the form of embodiment of the invention as herein disclosed, constitutes a preferred form, it is to be understood that other forms might be adopted, all coming within the scope of the 15 claims which follow.

What is claimed is as follows:

1. Air conditioning apparatus for a room or the like comprising a refrigerant evaporator, means for thermally contacting air to be conditioned for said room with said evaporator, a refrigerant liquefying unit connected in refrigerant flow relationship with said evaporator, said refrigerant liquefying unit including a refrigerant translating device located in said room, a 25 refrigerant condenser located outside said room and condensing refrigerant from said translating device, and means for dissipating heat from said translating device, said last named means utilizing a body of liquid refrigerant of substantially 30 less than condenser pressure evaporating and discharging into said liquefying unit.

2. Air conditioning apparatus for a room or the like comprising a refrigerant evaporator, means for thermally contacting air to be conditioned for said room with said evaporator, a refrigerant liquefying unit connected in refrigerant flow relationship with said evaporator, said refrigerant liquefying unit including a motor member and a refrigerant compressor member located in said room and a refrigerant condenser located outside said room and receiving refrigerant from said compressor member, and means whereby liquid refrigerant flows 35 in thermal contact with at least one of said members and in refrigerant circulating and phase changing relationship with said condenser.

3. Air conditioning apparatus for a room or the like comprising a refrigerant evaporator, means for thermally contacting air to be conditioned for said room with said evaporator, a refrigerant liquefying unit connected in refrigerant flow relationship with said evaporator, said refrigerant liquefying unit including a refrigerant translating device located in said room, a 40 refrigerant condenser located outside said room and condensing refrigerant from said translating device, means for dissipating heat from said translating device, said last named means utilizing a body of liquid refrigerant evaporating and discharging into said condenser, a motor-driven fan for said condenser and means responsive to 45 conditions in said room controlling the operation of said liquefying unit and motor-driven fan.

4. Air conditioning apparatus for a room or the like comprising a refrigerant evaporator, means for thermally contacting air to be conditioned for said room with said evaporator, a refrigerant liquefying unit connected in refrigerant flow relationship with said evaporator, said 50

refrigerant liquefying unit including a refrigerant translating device and a refrigerant condenser located in said room, a heat dissipator outside said room including a liquid evaporative element, means to circulate a liquid in thermal contact with said condenser to said evaporative element, and means to transfer moisture condensed on said evaporator to said evaporative element.

5. Air conditioning apparatus for a room or the like comprising a refrigerant evaporator, means for thermally contacting air to be conditioned for said room with said evaporator, a refrigerant liquefying unit connected in refrigerant flow relationship with said evaporator, said unit including a refrigerant translating device located in said room and a heat dissipating means located outside of said room, means to transfer moisture condensed on said evaporator to a spray-head located above said heat dissipating means, and means located below said heat dissipating means for collecting excess moisture which may not be evaporated by said heat dissipating means.

6. Air conditioning apparatus for a room or the like comprising a refrigerant evaporator, means for thermally contacting air to be conditioned for said room with said evaporator, a refrigerant liquefying unit connected in refrigerant flow relationship with said evaporator, said unit including a refrigerant translating device located in said room and a heat dissipating means located outside of said room, and means to transfer moisture condensed on said evaporator to a spray-head located above said heat dissipating means.

7. Air conditioning apparatus for a room or the like comprising a refrigerant evaporator, means for thermally contacting air to be conditioned for said room with said evaporator, a refrigerant liquefying unit connected in refrigerant flow relationship with said evaporator, said refrigerant liquefying unit including a motor member and a refrigerant compressor member located in said room and a refrigerant condenser receiving refrigerant from said compressor member, and means whereby liquid refrigerant flows 55 in thermal contact with at least one of said members and in refrigerant circulating and phase changing relationship with said condenser, said last named means including means for reducing the pressure of the liquid refrigerant which flows in thermal contact with said one member.

8. In combination; an evaporator; means flowing air to be conditioned over said evaporator; a refrigerant liquefying unit connected in refrigerant flow relationship with said evaporator; said liquefying unit comprising a motor member, a compressor member, and condensing means; means for flowing cooling water in thermal exchange with said condenser; and means whereby liquid refrigerant flows in thermal contact with at least one of said members and in phase changing relationship with said condenser, said last named means including means for reducing the pressure of the liquid refrigerant which flows in thermal contact with said one member.

ROBERT R. CANDOR.
